UNITED STATES PATENT OFFICE.

ALBERT H. HENDERSON, OF BALTIMORE, MARYLAND, ASSIGNOR OF ONE-THIRD TO
GEORGE T. KENLY AND ONE-THIRD TO CHRISTOPHER R. WATTENSCHIEDT, BOTH
OF BALTIMORE, MARYLAND.

COMBINED RAILWAY TIE AND TIE-PLATE AND ROD.

1,264,070.

Specification of Letters Patent. Patented Apr. 23, 1918.

Application filed September 5, 1917. Serial No. 189,740.

To all whom it may concern:

Be it known that I, ALBERT H. HENDERSON, a citizen of the United States, residing at Baltimore, in the State of Maryland, have 5 invented new and useful Improvements in Combined Railway Ties and Tie-Plates and Rods, of which the following is a specification.

This invention, in respect to the tie element, is of that class in which comparatively small blocks of wood are used with a metallic structure as supports for the rails whereby the advantages of a timber tie, while presenting a minimum quantity of wood, are secured. Such composite ties also, among 15 other advantages, have those of strength, of elasticity, of deadening sound, and of effecting insulation of the rails required when a signaling system is used involving track 20 circuits.

In the improved composite tie which forms a part of the combination forming my invention, the wooden blocks are so arranged in their respective pockets that the 25 upper surfaces of said blocks shall project above the upper edges of the metallic tie element whereby to prevent contact of the rails therewith. When the tie is placed on the roadbed and the ballast has been thrown 30 in, there is effected a fast and permanent interlocking engagement between the tie and ballast, holding the tie in position, it being firmly-embedded and anchored so that it cannot move or creep, the construction 35 and result being such that the tie forms a channel to receive and lock longitudinally and transversely with the ballast.

The element of the metallic tie-plate and rod which enters into the combination constituting this invention is an important factor, not only by reason of its individual construction, but in that it is provided with shoulders which abut against the inner 40 ends of the wooden blocks, whereby retention of the latter in position is assured in a marked degree.

In the accompanying drawings,—

Figure 1 is a perspective view showing a combination into which enter my improved 50 composite tie and tie-plate and rod. Fig. 2 is a cross section on the line 2—2 of Fig. 1. Fig. 3 is a plan view of the sheet metal blank from which the tie in one form is made. Fig. 4 is a top view of the tie-plate and rod blank. Fig. 5 is an enlarged end

view of Fig. 1. Fig. 6 is a longitudinal section of one end of the structure seen in the latter figure. Fig. 7 is a fragmentary perspective view suggestive of the formation of the tie of cast steel or other molded metal. 60 Fig. 8 shows a modification hereinafter referred to. Fig. 9 is a plan view showing a modified shape of the tie-plate blank indicated in Fig. 3. Fig. 10 is a plan view of the tie-plate and rod blank. Fig. 11 is 65 a fragmentary longitudinal section of a modified form of the combined structure. Fig. 12 is a central longitudinal section of the tie-plate and rod on the line 12—12 of Fig. 11, showing the inverted U-shaped 70 character of the central or rod member of said structure.

In carrying out my invention, so far as the structure of the metallic tie is concerned, I take a sheet of metal, preferably steel, 75 which by suitable machinery is stamped out to form a blank A as shown in Fig. 3, and thereafter by suitable means give it the channel or trough-like shape indicated in Fig. 1 and other figures. In Fig. 3 the bend 80 outline is represented by the dotted lines. In that figure the longitudinal central portion is solid as shown by 1, and at the longitudinal center of the blank are stamped out or formed openings 2. Similar but smaller 85 openings 3 are provided near the respective ends of the blank. Certain parts of the outer edges of the blank, and adjacent to the openings 3, are cut out as indicated at 4, while at each end of the blank portions 90 5 are removed, leaving extremities 6. The longitudinal central portion 1 is projected at each end so as to form continuations 7 which preferably extend slightly beyond the extremities 6. 95

Supposing Fig. 3 to represent the inner side of the blank A, points or spurs 8 are formed or projected by suitable means at each side of the blank in the portions 9, near the respective ends of the blank. Bolt holes 100 11 are made in the several parts of the superficial area as indicated. The stamping out of the blank, the forming of the points or spurs 8, and the perforating at 11 are or may be effected at one operation, or the 105 points or spurs 8 and the holes 11 may be produced after the stamping out of the metallic tie blank.

In Fig. 1 the steel or other metallic blank of Fig. 3 and hereinabove described, is seen 110

brought to substantially trough or channel shape, each outer end of the tie forming a pocket inclosing and clamping a block of wood 12 which, generally considered, is 5 usual in composite ties of this character. It will be found in Figs. 1 and 2, and understood from Figs. 6 and 11, that the points or spurs 8 at each side of the tie are embedded in a wooden block 12, and that the latter 10 is clamped and additionally secured in the pockets of the channel by bolts 14 which pass through holes 11 and are strained and tightened by means of nuts.

The removal of sections of the blank at 15 2 provides in the completed structure, in Fig. 1, open sides at the central portion of the tie, and similar removal at 3 results in the formation of smaller openings near the ends of the tie. The function of the openings formed at 2 is to permit the entrance 20 of ballast to the body, or what may be termed the interior, of the tie, whereby an effective anchor, lock or obstruction against longitudinal, creeping, or other movement of 25 the tie with reference to the road bed is insured. The continuations 7 also serve to interlock with the ballast, and it is to be noticed that the ends of the channeled portions of the tie project at 15 beyond the 30 outer ends of the blocks 12, and encroach upon the projections or feet 7 for the co-operation of the ballast in the anchoring of the ends of the tie with the road bed. Similar projections 15^a of the sides of the channel are provided beyond the inner ends of 35 the blocks 12, whereby the ballast resting upon the longitudinal central portion 1 may find its way up against the inner ends of the blocks 12 and be pocketed by the bottom 40 1 and the projections 15^a, thereby providing for the embedding and anchoring of the tie at its central portion in the road bed. Thus the tie is embedded and anchored in and held by the ballast so as to become practically 45 an integral part of the road bed, this embedding and anchorage being effected not only at the central portion of the tie, that is to say, between the rails, but also at the ends of the tie or beyond the track.

50 If desired, as a part of the means for preventing creeping or longitudinal movement of the blocks 12, a portion of the bottom 1 may be slit at the projections 7; that is to say, the solid projections 7 shown in 55 Fig. 1 may be cut, as indicated in Fig. 8, so as to allow a portion 7^a thereof to be turned up against the outer end of the block 12.

The open sided construction of the channeled tie serves also the important purpose 60 of allowing free drainage between the rails, and the consequent protection of the road-bed and the wooden blocks 12. The clamping bolts 14 are intended to draw tightly 65 together the sides of the channeled struc-

ture, clamping them upon the wooden blocks 12 and causing the effective penetration of the points or spurs 8 into the sides thereof.

In Fig. 1, and also in Figs. 2, 5 and 6, it will be observed that the blocks 12 extend 70 above the upper edges of the channeled tie, and more especially that the part of the wooden block upon which rests the tie plate, on which in turn the rail is placed, extends a considerable portion above the inner edge 75 formed at the cut-away portions 4. Thus sufficient space is provided between the foot of the rail and the metallic tie so that any sinkage by wear of the wood cannot result in contact of the rail with a metallic body. 80

Should it be desired to renew the wooden blocks 12 when worn, it is required, first, to release the bolts 14, whereupon the points or spurs 8 may be detached or forced from the wood when, after the removal of the end bolt 14, a block 12 may be withdrawn endwise as will be evident from Fig. 1. In the modification shown in Fig. 8 the turned up portion 7^a would necessarily have to be flattened. However, if desired, either block, 90 on the taking out of the ballast at the center of the tie, may be drawn inward and lifted out, it being understood that the obstructing bolts have been removed and the points or spurs forced from their hold upon the wood. 95

In Fig. 9 a blank similar to that described with respect to Fig. 3, is indicated, the main difference being that in Fig. 9 the central longitudinal portion 1 is lightened by the removal of a central section 2^a and also of 100 a section 2^b near each end of the blank. These removed portions may be of any desired size and shape and, as is obvious, their removal lightens or reduces the weight of the blank without materially impairing its 105 strength as a tie. This lightened form of blank may have advantages over the more solid form found in Fig. 3, inasmuch as it allows greater facilities for anchoring with the ballast, and also for carrying off drainage. Either form may commend itself to the practical engineer when considering the character of the rolling stock and the amount 110 of traffic intended to be provided for.

In Fig. 7 such a tie as is hereinbefore 115 described as stamped out of sheet metal, is shown as a casting of steel or other suitable material. The tie, whether stamped or cast, may be galvanized for its protection from exterior influences.

As has been stated, my present invention contemplates a combination between the composite, that is to say, metallic and wooden structure thus far described, and a metallic tie-plate and rod. This combination will be understood by reference, more especially, to Figs. 1, 6, 11 and 12, although shown to some extent in other figures. The tie-plate and rod, generally represented by B, is also stamped from a sheet of metal, 120 125 130

preferably steel, and is indicated in two equivalent forms in Figs. 4 and 10. In each the central or rod portion 20 of the blank, in the completed structure, is preferably 5 bent to the inverted U-shape shown by 20^a in Fig. 12, which is a section on the line 12-12 of Fig. 11. The outer ends 21 of the tie-plate section proper, see Figs. 1, 4 and 10, are of somewhat extended area, the un- 10 der side of each of said parts 21 being pro- vided with points or spurs 8^a which, as seen in Fig. 6, are embedded in the upper surface of one of the wooden blocks 12. The upper 15 surfaces of the parts 21 serve as the imme- diate seats for the flanges of the rails C, so indicated in Figs. 1, 2, 5, 6, 8 and 11. The rail having been laid upon the outer end of the plate member 21, certain tongues formed at the end of said plate are turned over 20 upon the respective sides of the flange of the rail whereby to clamp it to the tie-plate and supplement the work of the usual spikes a. Such tongues, in the blank tie plate and rod, Figs. 4 and 10, are shown by 22 and 23. 25 In Fig. 4 the left hand end of the tie-plate proper is seen provided with two exterior tongues 22 and one interior tongue 23, while the right hand end is furnished with one exterior tongue 22 and two inner tongues 23. 30 This system of illustration is to explain that it is optional with me to select the number and arrangement of these tongues. Thus in Fig. 10 each end of the tie-plate has three exterior tongues 22 and two inner ones 23. 35 It will be understood that in Figs. 4 and 10 the bending margins, whether of the central portion of the structure or of the tongues, are indicated by dotted lines. The disposition of the tongues is left to the discretion of the 40 engineer. The length of the tongue 22 or 23 will also be left to his judgment, in view of conditions to be encountered. Thus the tongues 22, 23 may be long enough to reach to the web of the rail, as indicated in Figs. 45 1, 6, 8 and 11, or have lesser lap upon the flange. It is obvious that these tongues do not interfere with the ordinary spiking which confines the tie-plate member and its superposed rail to the wooden block or 50 cushion 12.

The formation described, while primarily designed to give to the tie-plate and rod great inherent strength, serves other purposes. Thus, the cavity or channeled under 55 side of the central or rod member of the tie-plate and rod B receives and pockets a portion of the ballast, the structure thereby being effectually anchored with the road bed. Furthermore, the ends 25 of this inverted 60 U-shaped part of the rod member abut against the inner ends of the blocks 12, thereby coöperating as a lock with the points or spurs 8^a to prevent distortion of the track.

My combined tie and tie-plate and rod 65 may be used with a worn out wooden tie by

cutting the tie in the center and reversing the ends, the parts worn in the old tie by the flange of the rail not being used for the seat of the rail in my improved structure.

While the use of such points or spurs as 70 8 or 8^a is considered advisable and as adding to the efficiency of my invention, they may be omitted if desired.

This invention is believed to constitute a practical improvement consisting of a composite metallic and wood tie in operative combination with a unitary metallic tie-plate and rod, the whole structure forming a substantial effective and immovable seat for the rails, and lock with the road bed. 75

It is my intention to file a separate application for the composite metallic and wooden tie, and another for the unitary metallic tie-plate and rod, the combination of which two structures forms the subject matter of the present case. 80

Certain details entering into this invention, hereinbefore specifically described, may be varied in manner and form suggesting themselves to the skilled engineer or mechanic without involving invention. 90

While wood is mentioned as the substance of which the blocks 12 are made, any other material or combination of materials having sufficiently the function of wood in this use 95 may be substituted therefor, and therefore where wood is mentioned in the claims it is to be understood that its equivalent is to be included.

Having thus described my invention, I 100 claim:—

1. A metallic trough-shaped tie and a wooden block at each end thereof, combined with a metallic unitary tie-plate and rod the rod portion of which unit is provided with 105 shoulders each adapted to fit against the inner end of one of said wooden blocks, the end or tie-plate portions of said unit being of extended area for resting upon said wooden blocks and having tongues adapted 110 to be bent over the flanges of the supported rails.

2. A metallic trough-shaped tie having interior points or spurs, and a wooden block at each end of said tie adapted to be penetrated by said points or spurs, combined with a metallic unitary tie-plate and rod the rod portion of which unit is provided with shoulders each adapted to fit against the inner ends of one of said wooden blocks, 120 said tie-plate and rod having ends of extended area furnished with points or spurs to penetrate said wooden blocks and with tongues adapted to be bent over the flanges of the supported rails. 115

3. A metallic trough-shaped tie and a wooden block at each end thereof combined with a metallic unitary tie-plate and rod the rod portion of which is of inverted U-shape and provided with shoulders each 130

adapted to fit against the inner end of one of said wooden blocks, said unitary tie-plate and rod having ends of extended area to rest upon said wooden blocks and furnished with 5 tongues adapted to be bent over the flanges of the supported rails.

4. An open-sided trough-shaped metallic tie and a wooden block at each end of said tie and confined within the same, combined 10 with a unitary tie-plate and rod the rod portion of which unit is of inverted U-shape and provided with shoulders each adapted to fit against the inner end of one of said wooden blocks, said unitary tie-plate and 15 rod having ends of extended area to rest upon said wooden blocks and furnished with tongues adapted to be bent over the flanges of the supported rails, and bolts for drawing together the sides of the trough-shaped 20 tie.

5. An open-sided trough-shaped metallic tie having interior points or spurs, a wooden block at each end of said tie confined within the same and adapted to be penetrated by 25 the points or spurs thereof, combined with a metallic unitary tie-plate and rod the rod portion of which unit is of inverted U-shape and provided with shoulders each adapted to fit against the inner end of one of said 30 wooden blocks, said unitary tie-plate and rod having ends of extended area to rest upon said wooden block and furnished with tongues adapted to be bent over the flanges of the supported rails, and bolts for drawing 35 together the sides of the trough-shaped tie.

6. A trough-shaped metallic tie having open sides provided with integral points or spurs, and an open bottom, and a wooden 40 block at each end of said tie confined within the same and adapted to be penetrated by said points or spurs, combined with a metallic unitary tie-plate and rod the rod portion of which unit is of inverted U-shape 45 and provided with shoulders each adapted to fit against the inner end of one of said wooden blocks, said unitary tie-plate and rod having ends of extended area to rest upon said wooden blocks and tongues adapted to be bent over the flanges of the supported rails, and bolts and nuts for drawing 50 together the sides of the trough-shaped tie.

7. An open-sided metallic trough-shaped tie, formed of a stamped blank of sheet 55 metal, and a wooden block at each end of said tie confined within the same, combined with a metallic unitary tie-plate and rod the rod portion of which unit is of inverted U-shape and provided with shoulders each 60 adapted to fit against the inner end of one of said wooden blocks, said unitary tie-plate and rod having ends to rest upon said wooden blocks and furnished with tongues

adapted to be bent over the flanges of the supported rails, and bolts for drawing together the sides of the trough-shaped tie. 65

8. An open-sided metallic trough-shaped tie formed or stamped out of sheet metal and having integral points or spurs, and a wooden block at each end of said tie confined within the same and engaged by said points or spurs, combined with a metallic unitary tie-plate and rod the rod portion of which unit is of inverted U-shape and provided with shoulders each adapted to fit 70 against the inner end of one of said wooden blocks, said unitary tie-plate and rod having ends of extended area to rest upon said wooden blocks and furnished with integral points or spurs for penetrating said blocks 75 and with tongues adapted to be bent over the flanges of the supported rails, and bolts for drawing together the sides of the trough-shaped tie. 80

9. As a combined composite tie and tie-plate and rod, a metallic trough-shaped and open-sided metallic body, a wooden block clamped within each end of said body and so located within the same as to be longitudinally within the limit of its pockets, a metallic unitary tie-plate and rod the rod portion of which unit is of inverted U-shape, the construction and arrangement being such that the tie centrally and at each end thereof, and the tie rod by reason of its inverted U-shape, shall receive, lock, and anchor with the ballast whereby the combined structure is made practically a part of the road bed, and means for compressing the tie upon said wooden blocks and for causing 100 the embedding of the tie-plate and also the tie-rod and plate in said wooden blocks. 95

10. A metallic trough-shaped tie and a wooden block at each end thereof and clamped therein, the upper edges of said metallic trough-shaped tie being depressed below the plane in which rests the foot of the rail, combined with a metallic unitary tie-plate and rod the rod portion of which unit is provided with shoulders each adapted to fit against the inner end of one of said wooden blocks, the end portions of said unit being of extended area for resting upon said blocks and having tongues adapted to be bent over the flanges of the supported rails, 110 and means for compressing the tie upon said blocks and for causing the embedding of the tie and also the tie rod and plate in said wooden blocks. 115

In testimony whereof I affix my signature 120 in presence of two witnesses.

ALBERT H. HENDERSON.
